BEATING-MACHINE FOR FURS.

1,211,659.

Specification of Letters Patent.

Patented Jan. 9, 1917.

Application filed February 18, 1916. Serial No. 79,191.

To all whom it may concern:

Be it known that we, SAMUEL BARUCH, a citizen of the United States, and resident of New York, borough of Brooklyn, in the county of Kings and State of New York, (whose post-office address is 1078 East Fifteenth street, Brooklyn, New York,) MORRIS J. BARUCH, a citizen of the United States, and resident of New York, borough of Bronx, in the county of Bronx and State of New York, (whose post-office address is 1057 Hoe avenue, New York, N. Y.,) THEODORE LINDNER, a citizen of the United States, and resident of New York, borough of Brooklyn, in the county of Kings and State of New York, (whose post-office address is 140 Cornelia street, Brooklyn, New York,) and SAMUEL GOLDSMITH, a citizen of the United States, and resident of New York, borough of Bronx, in the county of Bronx and State of New York, (whose post-office address is 1792 Washington avenue, New York, N. Y.,) have invented new and useful Improvements in Beating-Machines for Furs, of which the following is a specification.

This invention relates to certain improvements in beating machines and more particularly to that type adapted for the beating, whipping or pounding of fur in order to soften the skin, to free and separate the hair which is matted down, and to loosen and dislodge dust, dirt or other impurities therein.

A machine embodying our invention may be employed not only for beating hides and unfinished furs, but may also be used for similarly treating articles or garments made of fur, or for treating clothing and the like.

Our invention involves various novel features of construction and arrangement of parts which will be pointed out more particularly hereinafter.

Among the main objects of our invention are the following: to limit and control the force of the blows; to impart to the article a shaking motion while it is being beaten; to facilitate the adjustment of the machine to receive articles of various sizes or thicknesses; and to so construct, support and operate the whipping or beating members that they will not readily be broken and will remain serviceable for a great length of time.

Various other objects and advantages will be pointed out hereinafter in connection

with a detail description of one embodiment 55 of our invention.

Reference is to be had to the accompanying drawing in which similar reference characters indicate corresponding parts in the several views.

In these drawings, Figure 1 is a top plan view of a machine constructed in accordance with our invention; Fig. 2 is a vertical longitudinal section taken substantially on the line 2—2 of Fig. 1; Fig. 3 is a vertical longitudinal section taken on the line 3—3 of Fig. 1; and Fig. 4 is a perspective view of a part of one of the whip supports.

In the specific form illustrated, we mount the parts on a main frame 10 which may be 70 of any suitable construction and supported in any suitable manner, as, for instance, by legs 11. The main frame supports a platform 12 upon which the articles to be beaten are placed. This platform may be of any 75 desired size dependent upon the character of the articles for which the machine is designed, but it preferably presents a flat supporting surface of considerable area. The platform is mounted so as to have resilient 80 vertical movement in respect to the frame.

Various different forms of spring connections between the platform and frame may be designed, but a simple arrangement involves the use of four coil springs 13, one 85 beneath each corner of the platform 12 and held in place by suitable studs or pins 14. The springs are of such strength that they normally hold the platform substantially in the position shown in Fig. 2 and do not permit any considerable lowering of the platform when ordinary articles are placed thereon. The beating of the articles on the platform will cause the platform to spring 90 up and down and this will aid in shaking 95 out any dust or dirt which may be loosened by the whipping or beating action. In order to protect and conceal the springs, the main frame may have a flange 15 extending upwardly around the periphery of the platform.

The main frame at the end opposite to the platform supports the whipping or beating mechanism. This is carried by an auxiliary frame 16 which is so connected to the portion 105 of the main frame carrying the platform that the beating mechanism may be adjusted vertically to permit articles of various

sizes to be placed on the platform beneath the beating mechanism. As shown, the main frame has two vertically extending bars or standards 17, 17, connected together at their upper ends by a bar 18. The auxiliary frame has bearing portions 19, 19, encircling these rods 17 and each bearing portion includes an adjustable clamping portion 20 whereby the auxiliary frame may be locked 10 rigid in respect to the vertical rods 17 and thus held in any desired vertical adjustment.

To facilitate the rapid movement of the auxiliary frame to the desired position, a screw 21 is mounted for free rotation in the cross bar 18 and has threaded engagement 15 in the base of the auxiliary frame 16 as shown particularly in Fig. 2. The upper end of the screw is provided with a suitable handle 22 whereby the screw may be rotated 20 and the auxiliary frame 16 raised or lowered.

Extending transversely of the frame 16 and supported in suitable brackets carried by the latter is a shaft 23 which may be 25 driven at the desired speed by an electric motor 24 or other suitable prime mover also carried by the auxiliary frame. As shown, the shaft of the motor is substantially in alinement with the shaft 23 but is separate 30 therefrom and speed reducing gearing 25 serves to transmit power from the motor to the shaft 23 and to operate the latter at the desired speed. The gearing may be interchanged to rotate the shaft 23 at the proper speed irrespective of the speed of the motor. 35

Adjacent to and slightly below the shaft 23 is a pivot rod 26 mounted in suitable brackets on the auxiliary frame. Pivoted on this rod are a series of arms 27 serving as 40 whip supports. Each arm is free to turn on the pivot rod independently of the other arms and each arm carries a whip and is so designed, mounted and supported that it is moved by the rotation of the shaft 23. As 45 shown, the shaft carries a series of cam fingers 28 in spaced relationship corresponding to the several arms 27. Each finger may have a collar 29 rigid therewith and encircling the shaft 23, and which may be locked 50 to the shaft in any desired angular relationship as for instance by means of set screws 29a. Each arm has a spring 30 tending to lift one end of the arm toward the shaft 23 and means are provided whereby the tension 55 of the springs may be readily adjusted. As shown, the shaft, pivot rod, and other moving parts are covered by a casing 31 and the springs 30 extend upwardly from the arms 27 to eye-bolts 32 extending down through 60 the top of the casing. A butterfly nut 33 or other suitable adjusting means is mounted on the upper end of each eye-bolt 32, whereby the tension of each spring may be increased or decreased at will. The springs 65 tend to draw the arms up so that they come

into the path of the cam fingers 28 on the shaft 23 and the latter act to force downwardly the adjacent portions of the arms as the shaft 23 rotates. To reduce friction and to facilitate the free operating of the 70 parts, each arm carries a roller 34 with which the corresponding cam finger engages. As shown, each arm has a slot extending lengthwise thereof and the roller is mounted on lugs extending upwardly at opposite 75 sides of the slot. Thus, after a cam finger engages with the roller and depresses the arm, it may pass into the slot and the arm may freely move upwardly again until the roller engages with the hub portion of the 80 cam finger. The fingers each have one substantially radial face and one curved or inclined face so that the rear end of each arm will be positively swung downwardly and then suddenly return under the action of the 85 spring as the roller passes down the radial side of the finger.

The arms are each pivotally supported intermediate of its ends, and the portion on the opposite side of the pivotal support 90 from the spring and roller, has a whip or beater clamping portion. As shown, a removable section 35 is clamped to the lower side of the arm by suitable bolts 36 and between the clamping portions are held the 95 base end of a whipping or beating rod 37 and supporting members 38 and 39. These guiding and supporting portions inclose the base of the whip and are clamped with the latter to the arm while their outer portions 100 are spaced slightly from the whip and are somewhat resilient, although neither as resilient nor as flexible as the whips themselves. The whips are preferably formed of fiber rods although bamboo or other suitable light flexible strips may be employed. The outer portions of the supports 38 and 39 may move with the rods 37 to a limited extent and thus prevent the rods from bending at a sharp angle at any one point. They 105 tend to strengthen or reinforce the base portions of the rods so that there is less liability of the latter being broken during the violent whipping or beating action.

In the use of the machine, the auxiliary 115 frame is adjusted to the proper height in respect to the platform 12 dependent upon the character of the articles to be treated. If the article be a skin or fur, the auxiliary frame will be so adjusted that the pivot rod 26 is at approximately the same plane as the platform 12 while if a muff or other larger or thicker object is to be treated, the auxiliary frame will be raised to a corresponding extent. Gearing is employed which will 120 give the whips or beaters the desired speed of operation and a preferable speed of operation is about the same as the maximum speed at which similar whips or beaters could be moved by hand if held firmly in the 125 130

latter. The cam fingers may be adjusted so that all of the whips will operate at the same time or they may be adjusted angularly about the shaft as shown in Fig. 3 so 5 that the several whips will operate in succession at uniformly spaced intervals.

It will be noted that the entire force of the blow which is delivered by each whip or beater is due to the tension of the spring 10 connected thereto. In other words, the cam fingers operate merely to lift the whips and the springs pull them down. Thus, the force of the blow may be varied at will by adjusting the tension of the springs and the 15 force of the blow is not in any way dependent upon the speed at which the machine is operated. The entire force of the blow of each whip may be delivered directly on to the article or stops may be employed in the 20 path of each arm to limit the swinging movement. Any suitable arrangement or construction might serve as a stop for all of the arms. For instance each roller might be limited in its upward movement by directly engaging with the collar which carries the corresponding cam finger. In fact, 25 this latter arrangement is preferable. By adjusting the auxiliary frame to a height somewhat above the platform, very light 30 blows may be delivered, each blow being due solely to the inertia of the whip after it reaches its normal lowered position.

Various changes may be made in the details of construction and in the arrangement 35 of parts without departing from the spirit of our invention or the scope thereof as defined in the appended claims. The particular machine shown in the drawings is to be considered merely as one embodiment of 40 our invention.

Having thus described our invention, what we claim as new and desire to secure by Letters Patent is:

1. A beating machine for furs or other 45 articles, including a platform, a plurality of whips or beaters, a pivotal support therefor, means for swinging said whips or beaters about said pivotal support, and means for relatively adjusting vertically said platform 50 and said support.

2. A beating machine for furs or other articles, including a platform, a frame, a 55 plurality of pivoted whips or beaters carried by said frame, means for vertically moving said whips or beaters, and means for vertically adjusting said frame in respect to said platform.

Copies of this patent may be obtained for five cents each, by addressing the "Commissioner of Patents, Washington, D. C."

3. A beating machine for furs or other articles, including a main frame, a platform carried thereby for supporting the articles 60 to be beaten, an auxiliary frame vertically movable in respect to said main frame, a plurality of beaters pivotally supported on said auxiliary frame, and a prime mover for operating said beaters. 65

4. A beating machine for furs or other articles, including a main frame, a platform mounted thereon, an auxiliary frame, vertical guides carried by said main frame, clamping members for holding said auxiliary frame to said guides, means for vertically adjusting said auxiliary frame along said guides and in respect to said main frame, a prime mover carried by said auxiliary frame, a shaft journaled on said auxiliary frame, reducing gearing between said prime mover and said shaft, a pivot rod carried by said auxiliary frame and substantially parallel to said shaft, a series of beater arms journaled on said rod, springs tending 80 to swing said arms toward said platform, and cams on said shaft for intermittently swinging said arms away from said platform. 75

5. A beating machine for fur or other articles, including a main frame presenting vertical guides, an auxiliary frame in engagement with said guides, means for vertically adjusting said auxiliary frame along said guides and in respect to said main frame, a 85 prime mover carried by said auxiliary frame, a shaft driven by said prime mover, a pivot rod carried by said auxiliary frame, a series of beater arms journaled on said rod, and means for swinging said beater arms 90 about their pivotal support upon the rotation of said shaft. 95

6. A beating machine for fur or other articles including a pivoted arm, a beater rod secured thereto and a pair of resilient supports carried by said arm and clamped at opposite sides of the base portion of said rod, said supports having divergent resilient portions extending lengthwise of said rod and spaced therefrom for limiting the swinging 100 movement of said rod in respect to said arm. 105

Signed at New York city in the county of New York, and State of New York, this seventeenth day of February, A. D. 1916.
